BELT CONVEYER CLEANER

Earl M. Glass, Pittsburgh, Pa.

Application September 20, 1946, Serial No. 698,135

3 Claims. (Cl. 198—230)

1

My invention relates to a cooling machine for doughnuts and the like.

An important object of the invention is to provide a doughnut cooler, including endless conveying means which are washed and dried during each cycle of operation of the machine, and therefore maintained in a sanitary condition at all times.

A further object is to provide a cooling machine for doughnuts, and the like, in which the conveying means are driven from a variable speed reduction unit, thereby affording variations in the cooling time.

A further object is to provide a cooling machine, in which it is unnecessary to disassemble the conveying means at each cleaning of the same.

A still further object of the invention is to provide a doughnut cooling machine which is highly sanitary, and in which the doughnuts need not be touched by hand at any time during the cooling operation.

Other objects and advantages of the invention will be apparent during the course of the following description.

In the accompanying drawings, forming a part of this application, and in which like numerals are employed to designate like parts throughout the same,

Fig. 1 is a vertical longitudinal section taken on line 1—1 of Figure 2, parts in elevation,

Figure 2 is a vertical transverse section taken on line 2—2 of Figure 1, parts in elevation,

Figure 3 is a fragmentary side elevation taken on line 3—3 of Figure 2, and,

Figure 4 is a plan view of one of the nozzles removed, parts sectioned.

In the drawings, where for the purpose of illustration, is shown a preferred embodiment of my invention, the numeral 6 designates a rectangular casing, including sides 7 and 8, ends 9, a bottom 10, and a top cover 11. The casing 6 is provided with a horizontal rectangular partition 12, spaced above the bottom 10, and also with spaced vertical partitions 13, for forming with the partition 12, bottom 10, sides 7 and 8, and ends 9, end hot water tanks 14.

Arranged within the tanks 14 are steam or hot water heating coils 15, having inlet and outlet branches 16 and 17, having inlet and outlet pipes 18 and 19.

Suitably rigidly secured to the top cover 11, and vertically inclined with respect thereto, and arranged within an elongated transverse opening 20 formed in the cover 11, is an inlet baffle 21.

2

The opening 20 and the baffle 21 extend transversely, for substantially the entire width of the casing 6.

Arranged within the casing 6 are pairs of vertically spaced rolls 22 and 23, near the ends 9 of the casing. The pairs of rolls 22 and 23 are vertically spaced and arranged in vertical alignment. The pairs of rolls 22 are vertically staggered in relation to the pairs of rolls 23. Arranged 5 near and inwardly from the pairs of rolls 22 and 23, are vertical groups of vertically spaced rolls 24 and 25. Each of the rolls 24 and 25 is spaced vertically equidistantly from the rolls of each adjacent pair 22 and 23.

Arranged near and spaced outwardly from and slightly above the uppermost pair of rolls 22, is a single roll 26. Arranged near and spaced beneath the lowermost pair of rolls 22, is a single roll 27. Arranged near and spaced outwardly 10 from and slightly above the uppermost pair of rolls 23, is a single roll 28. Arranged above the roll 28 and in alignment with the roll 26 and the pairs of rolls 25, is a single roll 29. Arranged near and spaced outwardly from and slightly 15 below the lowermost pair of rolls 23, is a single roll 30. Arranged inwardly from the roll 30, and slightly below the same, and in alignment with the rolls 25 is a single roll 31. Arranged centrally within the tanks 14 are drive rolls 32 and 33. All 20 of the above mentioned horizontal rolls are suitably mounted upon the sides 7 and 8 of the casing 6.

Arranged within the casing 6 are two endless flexible foraminous conveyor belts 34 and 35, 25 which are preferably formed of suitable stainless steel wire mesh.

The endless belt 34 passes about the drive roll 32, through an opening formed in the partition 12, over the roll 26, about the roll 29, about the uppermost pair of rolls 22, about the uppermost roll 25, about the second uppermost pair of rolls 22, about the second uppermost roll 25, about the third uppermost pair of rolls 22, about the third uppermost roll 25, about the fourth uppermost pair of rolls 22, about the lowermost roll 25, about the lowermost pair of rolls 22, about the roll 31, about the roll 27, and through an opening 30 formed in the partition 12. The endless belt 34, in passing about these rolls, forms a vertical upwardly moving run 36, and horizontal runs 37, 38, 39, 40, 41 and 42, all of which move horizontally to the right, in Figure 1 of the drawings.

The endless belt 35 passes about the drive roll 33, through an opening formed in the partition 12, over the roll 28, about the uppermost roll 24,

about the uppermost pair of rolls 23, about the second uppermost roll 24, about the second uppermost pair of rolls 23, about the third uppermost roll 24, about the third uppermost pair of rolls 23, about the fourth uppermost roll 24, about the lowermost pair of rolls 23, about the lowermost roll 24, about the roll 30, and through an opening formed in the partition 12. The endless belt 35, in passing about these rolls, forms a vertical upwardly moving run 43, and horizontal runs 44, 45, 46, 47, and 48, all of which move horizontally to the left in Figure 1 of the drawings.

It can thus be seen, that the horizontal runs of the endless belts 34 and 35, just described, travel in opposite horizontal directions, and due to the arrangement of rolls, the oppositely horizontally moving runs of the two endless belts are horizontally staggered. The horizontal runs which pass about the rolls 24 are spaced vertically between the horizontal runs which pass about the pairs of rolls 22; while the horizontal runs which pass about the rolls 25, are spaced vertically between the horizontal runs which pass about the pairs of rolls 23.

Rigidly secured within the casing 6, are vertical groups of vertically spaced and vertically inclined baffles 49 and 50. The inclined baffles 49 are adjacent to the forward or discharge ends of the horizontally moving runs 44, 45, 46, 47, and 48, while the inclined baffles 50 are adjacent to the discharge ends of the horizontally moving runs 37, 38, 39, 40, and 41. The lower ends of the baffles 49 extend slightly beneath the rolls 24, and the lower ends of the baffles 50 extend slightly beneath the rolls 25 and the roll 29.

Arranged slightly beneath the roll 31, and adjacent to the discharge end of the horizontal run 42 is an endless horizontal take-off conveyor belt 51, passing about a short horizontal roll 52, suitably mounted within the casing 6. The conveyor belt 51 is preferably formed of stainless steel wire mesh, and extends horizontally transversely of the endless belts 34 and 35, near one end 9 of the casing 6. The endless belt 51 has upper and lower runs which pass through an opening 53 in the side 8, and which pass about a drive roll, suitably arranged outside of the machine, and not shown in the drawings.

Rigidly secured to the sides 7 and 8 of the casing 6, are horizontal air nozzles 55, disposed outwardly of and near the vertical runs 36 and 43, to dry the same after passing from the hot water tanks 14. One end of each nozzle 55 is closed, while its opposite end is provided with an air inlet extension 56, which leads into an air fan box 57. Air is supplied to each fan box, under suitable pressure, by a rotary fan 58, driven by any suitable means. Disposed inwardly of and adjacent to the vertical runs 36 and 43, are vertical stationary baffles 59, disposed opposite the nozzles 55. Both the nozzles 55, and the baffles 59 extend throughout substantially the entire width of the endless belts 34 and 35.

The numeral 60 designates a motor which drives a variable speed reduction unit 61, which drives a main transverse drive shaft 62, carrying a pulley 63. This pulley is engaged by belts 64 and 65. The belt 64 engages a pulley 66, which drives the shaft 67 of the drive roll 32. The belt 65 drives a pulley 68, driving a gear 69, driving a reversing gear 70, which drives the shaft 71 of the drive roll 33.

The operation of the doughnut cooling machine is as follows:

Doughnuts, or the like, slide down the inlet baffle 21, through the opening 20 and onto the upper run 37 of the endless conveyor belt 34. These doughnuts reach the end of the upper run 37, and are discharged onto the upper inclined baffle 50 and onto the upper run 44 of the endless conveyor belt 35. The doughnuts are progressively carried by and dropped or discharged from the horizontal runs 44, 38, 45, 39, 46, 40, 47, 41, 48, and 42, during which process the cooling of the doughnuts takes place. The doughnuts are discharged from the horizontal run 42, onto the take-off conveyor belt 51, which conveys them outside of the machine, where they may be collected.

The endless belts 34 and 35 pass continuously through, and are subjected to the washing action of the hot water in the tanks 14. This water is heated by steam or hot water in the coils

25 15. As the endless belts 34 and 35 pass out of the tanks 14, they pass the transverse elongated air nozzles 55, which subject them to an air blast to dry them, and remove any remaining particles 30 of grease, or any crumbs still adhering. This continuous washing and drying operation maintains the stainless steel belts in a sanitary condition at all times. The air blast from the nozzles 55 strikes the stationary baffles 59, and creates air 35 turbulence within the casing 6, thus aiding in the cooling of the doughnuts. The stainless steel wire mesh conveyor belts do not tend to rust or corrode due to the continuous washing.

Through the variable speed reduction unit 61, the cooling time for the doughnuts may be adjusted and varied.

It is to be understood that the form of my invention herewith shown and described, is to be taken as a preferred example of the same, and 40 that various changes in the shape, size and arrangement of parts may be resorted to, without departing from the spirit of my invention or the scope of the subjoined claims.

Having thus described my invention, what I 45 claim is:

1. A doughnut cooling machine, comprising a casing, hot water tanks arranged within the casing near its bottom and opposite ends, drive rolls arranged within the hot water tanks, spaced substantially horizontal rolls mounted within the casing above the hot water tanks, flexible conveyor belts passing about the drive rolls and about the spaced rolls and including vertically spaced horizontally staggered runs moving in opposite directions, and air nozzles mounted within the casing near and above the hot water tanks for drying the flexible conveyor belts as they pass from the tanks.

2. A doughnut cooling machine, comprising a casing including spaced partitions forming hot water tanks near the bottom and opposite ends of the casing, heating coils associated with the casing and arranged within the tanks, drive rolls mounted within the tanks, spaced rolls mounted 60 within the casing and arranged above the tanks, endless foraminous belts passing about said drive rolls and said spaced rolls and including horizontally staggered oppositely moving runs, inclined baffles adjacent to the discharge ends of the runs, a take-off conveyor adjacent to the discharge end of the lowermost run and arranged transversely of the endless foraminous belts, and air nozzles carried by the casing and arranged near and above the tanks for drying the endless foraminous belts as they pass from the tanks.

70 75 775

3. A cooling machine for doughnuts, comprising a casing having an inlet opening, hot water tanks within the casing and near the bottom of the same, heating coils arranged within the hot water tanks, drive rolls mounted within the hot water tanks, variable speed driving means for the drive rolls and arranged outside of the casing, spaced rolls mounted within the casing and arranged above the tanks, endless flexible foraminous conveyor elements passing about the drive rolls and about the spaced rolls and including oppositely moving vertically spaced horizontal runs, inclined baffles adjacent to the discharge ends of the spaced horizontal runs, take-off conveyor means adjacent to the discharge end of the lowermost horizontal run and passing outside of the casing, elongated air nozzles mounted

within the casing adjacent to the endless conveyor elements and near the tanks and adapted for drying the endless conveyor elements as they pass from the tanks, and fans associated with the casing for supplying air to the nozzles.
